(57) **CLAIM**

The ornamental design for a filter cap for electric cleaner, as shown and described.

DESCRIPTION

FIG. 1 is a perspective view of a filter cap for electric cleaner showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is an exploded perspective view thereof; and,

FIG. 9 is a perspective view thereof, the broken line showing being for illustrative purposes only and forming no part of the claimed design.
